GOLF BAG SUPPORT

Filed May 13, 1930

UNITED STATES PATENT OFFICE

WILLIAM H. GUNTHER, OF SAN FRANCISCO, CALIFORNIA

GOLF BAG SUPPORT

Application filed May 13, 1930. Serial No. 451,937.

My invention relates to a new and useful golf-bag support which is particularly adapted for use on the links to maintain the bag in a substantially upright position while the golfer is making each shot, and thereby to facilitate the exchange and replacement of, and the general access to the clubs contained in the bag.

It has been the practice heretofore, in the absence of a caddy, to throw or lay the bag down on the ground prior to making a shot, and when it was desired to exchange or replace a club, it was necessary to stoop or bend down to pick up the bag and hold it up while the exchange was being effected.

To obviate these disadvantages, I have devised a novel golf-bag support which will maintain the golf-bag in an upright position while the golfer is playing, and one which will automatically fold up against or parallel to the bag while the latter is being transported over the course after each shot.

My invention further relates to a novel support of this character, which functions practicably and effectively without regard to the surface or topography of the turf on which the bag is supported.

My invention further relates to a novel golf-bag support which is of an extremely simple, durable and inexpensive construction, and which requires no skill or effort in its manipulation.

My invention further relates to a novel support which may be detachably or permanently attached to a golf-bag, and which can be manufactured and sold independently of the golf-bag proper.

To the above ends, my invention consists of an inner plate secured to the inner upper edge of a golf-bag; an outer plate secured to said inner plate on the outer upper edge of said bag; upper diverging U-shaped or forked members carried by the upper edge of said outer plate; a keeper carried by the bottom end of said outer plate; a pair of legs pivoted at their upper ends in said forked members; springs for tensioning said legs; and a sliding lever engaging said legs and adapted to serve as a latch for engaging the keeper on the bottom end of said outer

plate to lock said legs in their inoperative, folded position.

My invention further consists of means for limiting or predetermining the range of movement of said legs with respect to the golf-bag.

For the purpose of illustrating my invention I have shown in the accompanying drawing one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the accompanying drawing:

Fig. 1 is a side elevational view of a golf-bag support embodying my invention shown in actual use;

Fig. 2 represents, on an enlarged scale, a front elevation of the upper portion of a golf-bag provided with a novel support embodying my invention;

Fig. 3 is a sectional view taken on line 3—3 of Fig. 2;

Fig. 4 is a sectional view taken on line 4—4, Fig. 2;

Fig. 5 is a plan view of the inner supporting plate forming part of my invention;

Fig. 6 is a plan view of the combined operating lever and latch forming part of my invention;

Fig. 7 is a modified form of my combined lever and latch construction shown in Fig. 6; and

Fig. 8 is a plan view, on an enlarged scale, of a blank from which the upper sleeves carrying the legs supporting the golf bag may be formed.

Referring to the drawing, in which similar numerals of reference indicate corresponding parts, 1 designates a golf-bag of my conventional construction, to the upper outer end of which is secured the outer supporting plate 2 by means of the screws or bolts 3 which pass through the wall of the bag and through an inner supporting plate 4, the

inner ends of said bolts or screws being retained by suitable nuts 5, it being understood that the manner of securing the supporting plate 2 to the upper portion of the golf-bag 1 may be varied without departing from the scope of my invention. The supporting plate 2 is provided with the upper U-shaped lugs or forked members 5a which diverge slightly, as will be seen from Fig. 2, and which serve as pivot points for the legs 6. The legs 6 preferably consist of rods of the desired length and thickness, the upper ends of said rods being driven into the sleeves or tubular members 7 which are provided with the upper forked portions 8 which fit within the U-shaped lugs 5a on the upper edge of the supporting plate 2. The forked ends 8 of the sleeves 7 which carry the legs 6 are pivoted to the U-shaped lugs 5a by means of the bolts or pins 9 to permit of a swinging movement of the legs 6 with respect to the golf-bag 1. The legs 6 are held in a normal, folded, inoperative position with respect to the golf-bag 1 by means of springs 10 which are anchored to fixed points 11 at the bottom of the U-shaped lugs 5a and to fixed points 12 in the inner lower portions of the sleeves 7. The action of these springs is to maintain the legs 6 in the folded position seen in Figs. 3 and 4. In the lower inner portions of the sleeves 7 I provide the slots or openings 13 through which extends an arcuate lever or member 14 which is provided with an upwardly and outwardly extending handle 15. The arcuate member 14 is provided with the end lugs 16 which form stops for limiting the range of movement of the legs 6 in the manner hereinafter described. The bottom of the arcuate member 14 serves as a latch to engage the keeper 17 at the bottom edge of the supporting member 2 to lock the legs 6 in their folded, inoperative position.

The operation is as follows: When it is desired to support a golf-bag equipped with my novel supporting device in the position illustrated in Fig. 1, it is merely necessary to exert an upward pull on the handle 15 of the arcuate member 14. This can be accomplished by merely attempting to lift the bag full of clubs by means of the handle 15, the weight of the clubs serving to exert the necessary pressure. The upward pressure on the handle 15 releases the bottom edge of the arcuate member 14 from engagement with the keeper 17 on the supporting plate 2 and results in extending the legs 6 into a diverging position away from the bag 1 so that said legs in conjunction with said bag form a tripod arrangement, as will be understood from Fig. 1. In this position the bag is firmly supported in the vertical position, thereby rendering the clubs contained in said bag immediately and readily accessible and eliminating the necessity for

the aid or service of a caddy. To prevent the undue distention or spacing of the legs 6 by the exertion of undue upward pull or pressure on the handle 15 I provide the lugs 16 which serve as stops so that the maximum distance to which the legs 6 can be spread or distended away from the bag 1 is limited or predetermined by the length of the arcuate member 14 or the total distance between the lugs 16. When the bag is raised off the ground from the position shown in Fig. 1 the springs 10 serve to return the legs 6 into their folded position in proximity and parallel to the bag 1, see Figs. 3 and 4, and the bottom edge of the arcuate member 14 rides on the outer inclined surface of the keeper 17 and automatically engages said keeper in the manner shown in Fig. 3 to lock the legs 6 in their folded, inoperative position, thereby relieving the strain on the springs 10 and preventing any accidental, undesired movement or displacement of the legs 6. In order to permit the engagement and disengagement of the arcuate member 14 with the keeper 17, the apertures or slots 13 in the inner lower portions of the sleeve 7 are made large enough to afford the necessary play. The forked ends 8 of the sleeves 7 are cut away at 18 for the purpose of permitting a limited swinging movement of the legs 6 carried by the sleeves 7.

It will thus be seen that I have devised a novel golf-bag support which is automatic in its operation, said support being brought into operative or effective position by merely raising the golf-bag by means of the handle 15 which results in spreading the legs 6 into diverging positions with respect to the bag. On the other hand, the lifting of the bag off the ground results in the automatic return of the legs 6 into a folded position through the agency of the springs 10, said legs being then locked into the inoperative folded position by engagement of the arcuate member 14 with the keeper 17 on the bottom of the supporting plate 2.

The present invention is an improvement upon the construction covered by my previous Patent No. 1,738,242, dated December 3, 1929, the structure disclosed in the present application differing from the structure of my prior patent in various respects, all as herein above pointed out.

It is further apparent that my novel golf-bag support may be built in or attached to the golf-bag during the process of manufacturing, or my novel support can be sold as a separate, independent unit which can be easily and quickly installed upon the upper portion of a golf-bag, as may be desired.

If desired I may provide the sleeve 7 with the set screws 20 which engage the rods forming the legs 6 of my novel bag support, whereby the length of said legs may be adjusted with reference to the size of the bag 1 or with

reference to the topography of the golf links or particular inclination at which it may be desired to set the golf-bag.

In Fig. 7, I have shown a modified form of the combined sliding lever and latch 14 wherein I provide notches or recesses 19 for the purpose of engaging the bottom portions 21 of the brackets which form the apertures 13, thereby locking the legs 6 in their inoperative folded position. If this construction is used the keeper 17 formed on the bottom end of the supporting plate 2 may be dispensed with. While the details of mechanical construction shown in Fig. 7 differ slightly from the showing of Fig. 2, it will of course be understood that the purpose or function in both instances is the same.

The sleeves 7 may, if desired, be formed by bending or deflecting the lower portion of the blank 22, shown in Fig. 8, into a tubular form, said blank being provided with slots 13 for receiving the combined latch and lever 14 and with the holes 23 which receive fastening devices for retaining the blank 22 in the desired tubular shape. This method of making the sleeves 7 is less expensive than casting and produces a lighter construction without detracting from its efficiency or appearance. The upper portions of the blanks 22 carry the forked ends 8 which engage the U-shaped lugs 5a, in a manner similar to that shown in Figs. 2, 3, and 4.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new, and desire to secure by Letters Patent, is:

45 1. In a device of the character stated, a plurality of legs adapted to be hinged to a golf-bag, springs bearing on the upper portions of said legs, a lever engaging to and sliding upon the upper, inner portions of said legs and adapted, when pulled, to diverge said legs into operative position with respect to said bag, and means carried by the upper portion of said bag and adapted to engage said sliding lever to lock said legs in inoperative position with respect to said bag.

2. In a device of the character stated, a plurality of legs adapted to be hinged to the upper portion of a golf-bag, springs bearing on the upper portions of said legs normally to retain said legs in inoperative, folded condition with respect to said bag, a lever engaging and sliding upon the upper portions of and adapted to diverge said legs into spaced, operative positions with respect to said bag, means on the ends of said lever adapted to

engage said legs for limiting the movement of said legs with respect to said bag, and means on the upper end of said bag adapted to engage said lever when the legs are folded against said bag to insure positive locking 70 of said legs in their inoperative position.

3. A golf bag support comprising a plurality of legs hinged to the upper end of said bag, a plurality of springs having their ends anchored in said bag and said legs and adapted normally to retain said legs in folded position against said bag, there being slots in the upper, inner portions of said legs, an operating lever engaged in said slots and adapted to slide upon the inner, upper portions of said legs to diverge the latter into a tripod position with respect to said bag against the tension of said springs, a keeper on said bag positioned below said slots and adapted to engage said lever to insure positive locking of said legs in their inoperative position, and lugs on the ends of said lever adapted to engage said legs to limit their movement with respect to said bag.
